BUILDING UNIT

Erle T. Putnam, Detroit, Mich., assignor to
 Libbey-Owens-Ford Glass Company, Toledo,
 Ohio

Application June 11, 1937, Serial No. 147,691.

14 Claims. (Cl. 72—18)

The present invention relates to an improved type of building unit primarily adapted for use in the construction of the exterior walls of buildings.

The building unit of the invention consists briefly of a composite block comprising a body portion formed from a plastic material such as concrete or the like, and an ornamental facing therefor consisting preferably of a sheet or plate of opaque glass, although ceramic tile may be used in some instances if desired. The ornamental face plate is firmly secured to the body portion by an interposed layer of adhesive material such as asphaltic mastic cement and also by mechanical fastening means in the form of metal frame members engaging both the ornamental face plate and body portion. In constructing a wall with building blocks of the invention, the blocks are laid up in courses in substantially the same manner as cut stone, granite, or terracotta, being preferably anchored to a rear or foundation wall.

An important object of the invention is the provision of improved means for mechanically securing the glass or other ornamental face plate to the body portion of the block in a manner to firmly lock the said facing and body portion together whereby all danger of the facing becoming accidentally displaced will be eliminated.

Another important object of the invention is the provision of mechanical fastening means engaging both the glass or other ornamental face plate and the body portion and being of such construction and arrangement that when the blocks are laid up in courses in a wall, the face plates will not support any of the structural load of the wall, thereby reducing to a minimum liability of breakage or chipping of the said facing.

Still another important object of the invention is the provision of mechanical fastening means for securing the face plate to the body portion in combination with a layer of suitable adhesive material between the facing and body portion which serves not only to bond the said facing to said body portion, but also to cushion the facing against shock and blows while at the same time permitting relative expansion and contraction of the facing and body portion to minimize breakage or loosening of the former.

Still another important object of the invention is the provision of a building block of the above character wherein the glass or other ornamental face plate is provided with a cushioned edge which protects the edges of the said face plate from chipping or spalling during the setting of the block in place in the wall.

Other objects and advantages of the invention will become more apparent during the course of the following description when taken in connection with the accompanying drawings.

In the drawings wherein like numerals are employed to designate like parts throughout the same,

Fig. 1 is a front elevation of a portion of a wall constructed in accordance with the invention;

Fig. 2 is a front view of one of the glass or other ornamental face plates and the metal frame members associated therewith, the face plate being partially broken away to more clearly show the frame members;

Fig. 3 is a vertical sectional view through the wall taken substantially on line 3—3 of Fig. 1;

Fig. 4 is a plan view of one of the metal blanks from which the frame members are formed;

Fig. 5 is a perspective view of one of the metal frame members stamped from the blank shown in Fig. 4;

Fig. 6 is a vertical sectional view through a portion of a wall embodying a slightly modified form of block; and

Fig. 7 is a view similar to Fig. 6 but showing still another form of block.

With reference to the drawings and particularly to Figs. 1 to 5, in which is disclosed one form of block provided by the invention, A designates the rear or foundation wall and B the front or exterior wall constructed of the improved building blocks. While the rear wall A is shown as consisting of conventional bricks or blocks 10 laid in the usual manner with mortar 11, the said wall 30 may be of any other desired construction.

The building blocks used in constructing the exterior wall B may be of any desired contour but, as shown in Fig. 1, the said blocks, designated in their entirety by the numeral 12, are 40 rectangular, and this is of course the most conventional shape, although they may obviously be of any particular shape or shapes desired. Each building block 12 is of a composite construction comprising a body portion 13 formed of 45 a plastic material such as concrete or the like, and an ornamental facing 14 preferably consisting of a sheet or plate of opaque glass, although ceramic tile or face plates of other materials may be used in some cases. Therefore, while the face 50 plate will be hereinafter referred to as being of glass, it will be understood that a face plate of any desired satisfactory material may be employed without departing from the invention.

The glass face plate 14 covers substantially the 55

entire front surface of the concrete body portion 13 and interposed between the said facing and body portion is a relatively thick, substantially uniform layer of adhesive material 15 preferably 5 an asphaltic mastic cement which serves not only to bind the facing to the body portion, but also permits relative expansion and contraction between the two without danger of the face plate becoming broken or accidentally displaced. The 10 layer of adhesive material 15 also serves to cushion the face plate against shock and blows, thereby increasing its resistance to breakage.

Arranged at each edge of the face plate 14 is a metal holder of the construction shown in Fig. 15 5, and these holders cooperate to form a frame extending entirely around the perimeter of the block for mechanically securing the said face plate to the body portion. Each of these holders or frame members comprises a longitudinally extending channel shaped portion 17 which, as best shown in Fig. 3, is received between the face plate 14 and body portion 13 of the block. The outer wall 18 of the channeled portion 17 constitutes a shoulder which abuts the rear surface of the face 20 plate, and extending forwardly therefrom and at substantially right angles thereto is a flange 19 disposed opposite the respective edge of the face plate and terminating in an inwardly directed lip 20.

30 The edges 21 of the face plate 14 are square with the opposite surfaces of said face plate and secured thereto is a strip 22 of some suitable resilient material, preferably an asphalt impregnated cork strip, although it may be of rubber, rubber composition, etc. These strips serve to protect the edges of the face plate and act as a cushion to prevent chipping or spalling of said face plate during the setting of the block in place in the wall. For instance, it has been found 35 that when setting blocks of this character, it is often necessary to place a tool between adjacent blocks and use it as a wedge to move the blocks into the exact desired position. Due to the provision of the strips 22, this moving or shifting 40 of the blocks to the desired position can be effected without danger of chipping or spalling the edges of the face plates. It will be noted, upon reference to Fig. 3, that the cork strip 22 terminates inwardly of the outer surface of the 45 face plate and that the shoulder 18, flange 19, and lip 20 of the metal frame member define a substantially U-shaped channel in which the said strip 22 is received. This strip is firmly secured to the edge of the face plate by a suitable adhesive and is relatively thicker than the width of the lip 20 so that while the lip extends over or overlaps the forward edge of the strip, it does not contact with the edge of the face plate.

60 The inner wall 23 of the channeled portion 17 constitutes a shoulder which engages the outer surface of the body portion 13, said shoulder projecting slightly beyond the outer shoulder 18, and extending at right angles with respect thereto is a relatively wide, flat, load bearing surface 65 24 which is disposed opposite the body portion of the block. Formed integral with and constituting a continuation of the load bearing surface 24 is an inwardly directed flange 25 having a plurality of angular portions which are embedded 70 and effectively tie into the concrete body portion 13.

Each metal frame member may be stamped in a single operation from the form of blank illustrated in Fig. 4, the said blank being bent along 75 the broken lines to form the different parts of

the said frame member, the same reference numerals being used in Fig. 4 as in Fig. 5 to indicate the corresponding parts. The use of a blank of the shape shown in Fig. 4 results in the metal frame member being mitered at each end when the blank is formed as illustrated in Fig. 2. 5

In the manufacture of the block 12, the glass face plate 14 is first laid horizontally on a support and one of the metal frame members positioned at each side of the face plate so that the outer shoulder 18 of the channeled portion 17 rests upon the rear surface of the face plate while the lip 20 fits around the cushioning strip 22. Clamping means are provided for holding the metal frame members in proper position and the flanges 19 thereof in firm, snug engagement with the strips 22. The mastic or other adhesive material 15, in a semi-liquid state, is then poured upon the back of the face plate to cover substantially the entire surface thereof and to 20 form a layer of a thickness approximately equal to the depth of the channeled portion 17. The cement or other plastic material forming the body portion 13 is then deposited on top of the layer of mastic to cover the same and to 25 completely fill the space defined by the metal frame members. A mold is also built up around the frame members to permit the molded body portion 13 to be made considerably thicker than the width of the said frame members, as shown 30 in Fig. 3, and when this is done it will be seen that the flanges 25 of the frame members will be embedded in the body portion. After the body portion has set, the mold and clamping means are removed and the block is ready for use. 35 While it is preferred to use cement for the body portion, the said body portion may be made of any suitable material or mixture of materials.

In constructing the wall B, the blocks 12 are laid up in courses in much the same manner 40 as cut stone, granite, or terra cotta, being preferably mechanically anchored to the rear wall A in some suitable manner such as by means of tie members 26. These members are shown as consisting of corrugated, flexible metal strips 45 embedded in the body portion 13 of the block and also in the mortar 11 between the blocks 10 of the rear wall A. The advantage in making the tie members 26 flexible is so that if the joints in the rear wall A do not coincide with the spacing 50 of the tie members, the said tie members can be bent to conform to the joints in the rear wall as shown in Fig. 3. In laying the blocks 12 of wall B, they are preferably spaced from the wall A and interposed between the two is a layer of 55 mortar 27.

Due to the fact that the load bearing surfaces 24 of the metal frame members project beyond the edges of the face plate 14, there will be formed around the edges of the body portion 13 a continuous ledge 28 which also projects slightly beyond the edges of the said face plate, as a result, when the blocks are laid up in courses in a wall, the load bearing surfaces 24 of vertically adjacent blocks will engage one another 65 while the edges of the adjacent face plates will be spaced slightly from each other, and in this space is adapted to be inserted a suitable caulking material 29. This caulking material may be applied by means of a spray gun and will ordinarily fill the mating channels 17 of adjacent frame members. With such a construction, the structural load of the wall will be supported entirely by the body portions 13 of the blocks, with none of the load being placed upon the face 70 75

plates 14. In other words, the load of one block is transferred directly to the next lower block, and each block takes the full strain of the blocks above it. Since it is impossible for the vertically adjacent face plates to engage one another when the blocks are put in place, the strain upon the said face plates will be reduced to a minimum, thereby eliminating breakage and chipping thereof. While the load bearing surfaces 24 are shown in Fig. 3, as directly contacting one another, they may be slightly spaced by a relatively thin layer of mortar, therebetween, and in such case the load of one block will be transferred to the next lower block directly through this layer of mortar.

The construction of the block is such that the face plate does not support any of the load when the block is set into the wall and the layer of adhesive material between the face plate and body portion takes care of any differences in expansion and contraction between the two materials, thus minimizing danger of breakage of the face plate under expansion or contraction. Also, the uniform layer of adhesive material 15 provides a cushion for the face plate to minimize the liability of breakage thereof. By the combination of mechanical fastening means and adhesive material, the face plate is firmly secured to the body portion with practically no danger whatever of its becoming accidentally displaced.

When the blocks are mounted in place, the body portions 13 of vertically adjacent blocks will also be spaced from one another inwardly of the load bearing surfaces 24 and this space can be filled with a layer of mortar 30. As the lips 20 of the metal frame members are disposed slightly inwardly of the outer surface of the glass face plate, the caulking material 29 will conceal the said lips and give the appearance of a wall built up of only the glass face plates, as these plates will be the only parts of the blocks exposed to view. This will result in a wall of exceptionally pleasing and attractive appearance. The caulking material 29 is also adapted to be inserted in the vertical joints between horizontally adjacent blocks.

In Fig. 6 is illustrated a slightly different form of block which includes all of the novel features and advantages of the form of block described above, and the same reference numerals are used to designate the corresponding parts. The only difference between this form of block and the block shown in Fig. 3 is that in Fig. 6 the edges 21 of the glass face plates 14 are beveled outwardly and the inner surfaces of the cushioning strips 22 are correspondingly beveled. However, the outer surfaces of the cushioning strips are square with the opposite surfaces of the face plate, as in Fig. 3, so that the same metal frame members may be used. The advantage of this particular construction is that by beveling the edges of the face plate and the inner surfaces of the strips 22, a more positive gripping action is obtained between the said face plate and strips to more firmly hold the face plate against possible accidental displacement.

In Fig. 7 is disclosed still another form of block in which the cushioning strips 22 are eliminated as are also the lips 20 on the metal frame members. In lieu thereof, the edges 21 of the face plates are outwardly beveled while the flanges 19 of the metal frame members are arranged at an acute angle with respect to the shoulders 18 so as to snugly fit over said beveled edges,

thereby firmly tying the face plate to the body portion.

A separate application has been filed to cover the apparatus originally disclosed in this application for use in the manufacture of the building blocks herein provided and which disclosure was subsequently cancelled in compliance with the requirement for division. Said divisional application is Serial No. 358,150, filed Sept. 24, 1940, entitled "Apparatus for use in the manufacture of building blocks."

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

I claim:

1. A building block of the character described comprising a body portion formed from a plastic material, a face plate covering a surface of the body portion, cushioning strips engaging the edges of the face plate, and fastening means having portions overlapping the forward edges of said strips but spaced from the edges of said face plate and other portions engaging the body portion for securing the face plate to the body portion, said fastening means projecting beyond the edges of the face plate so that when the blocks are laid up in courses in a wall, the said face plates do not support any load, a portion of said fastening means engaging the rear surface of the face plate for spacing the said plate from said body portion.

2. A building block of the character described comprising a body portion formed from a plastic material, a face plate covering a surface of the body portion, cushioning strips engaging the edges of the face plate, and fastening means for securing the face plate to the body portion including a metal frame member arranged at each edge of the block and having portions overlapping the forward edges of said strips but spaced from the edges of said face plate and other portions embedded in the body portion, said frame members projecting beyond the edges of the face plate to provide load bearing surfaces so that when the blocks are laid up in courses in a wall, the said face plates do not support any load, each of the said frame members having a portion engaging the rear surface of the face plate for spacing the said face plate from said body portion.

3. A building block of the character described comprising a body portion formed from a plastic material, a face plate covering a surface of the body portion, cushioning strips engaging the edges of the face plate, and fastening means for securing the face plate to the body portion including a metal frame member arranged at each edge of the block and having portions overlapping the forward edges of said strips but spaced from the edges of said face plate and other portions embedded in the body portion, said frame members projecting beyond the edges of the face plate to provide load bearing surfaces so that when the blocks are laid up in courses in a wall, the said face plates do not support any load, each of the said frame members having a portion disposed between the face plate and body portion for spacing the former from the latter, and a layer of adhesive material filling the space between the said face plate and body portion.

4. A building block of the character described

- comprising a body portion formed from a plastic material, a face plate covering a surface of the body portion, cushioning strips engaging the edges of the face plate, and fastening means for securing the face plate to the body portion having channel portions overlying the edges of the face plate and receiving the cushioning strips therein and other portions engaging said body portion, said fastening means projecting beyond the edges of the face plate so that when the blocks are laid up in courses in a wall, the said face plates do not support any load.
5. A building block of the character described comprising a body portion formed from a plastic material, a face plate covering a surface of the body portion, cushioning strips engaging the edges of the face plate, and fastening means for securing the face plate to the body portion including a metal frame member arranged at each edge of the block and having a channel portion overlying the edge of the face plate and receiving the respective cushioning strip therein and other portions embedded in the body portion, said frame members projecting beyond the edges of the face plate to provide load bearing surfaces so that when the blocks are laid up in courses in a wall, the said face plates do not support any load, each of said frame members having a portion engaging the rear surface of the face plate for spacing the said plate from said body portion.
6. A building block of the character described comprising a body portion formed from a plastic material, a face plate covering a surface of the body portion, cushioning strips engaging the edges of the face plate, and fastening means for securing the face plate to the body portion including a metal frame member arranged at each edge of the block and having a channel portion overlying the edge of the face plate and receiving the respective cushioning strip therein and other portions embedded in the body portion, said frame members projecting beyond the edges of the face plate to provide load bearing surfaces so that when the blocks are laid up in courses in a wall, the said face plates do not support any load, the said frame members having portions disposed between the face plate and body portion for spacing the former from the latter, and a layer of adhesive material filling the space between the said face and body portion.
7. A building block of the character described, comprising a body portion formed from a cementitious material, a face plate covering a surface of the body portion, cushioning strips engaging the edges of the face plate, and fastening means for securing the face plate to the body portion including a metal frame member arranged at each edge of the block and having portions overlapping the forward edges of said cushioning strips but spaced from the edges of the face plate and other portions engaging said body portion, said frame members having portions projecting beyond the edges of the face plate in a plane parallel with the plane of said face plate to provide load bearing surfaces so that when the blocks are laid up in courses in a wall the said face plates do not support any load.
8. A building block of the character described, comprising a body portion formed from a cementitious material, a face plate covering a surface of the body portion, cushioning strips engaging the edges of the face plate, and fastening means for securing the face plate to the body portion including metal frame members arranged at the edges of the block and each having a portion embedded in said body portion; a shoulder engaging the rear surface of said face plate, and a lip opposite the edge of said face plate but spaced therefrom and cooperating with said shoulder to form a channel overlying the edge of said face plate and receiving the respective cushioning strip therein, said frame members having portions projecting beyond the edges of the face plate in a plane parallel with the plane of said face plate to provide load bearing surfaces so that when the blocks are laid up in courses in a wall the said face plates do not support any load.
9. A building block of the character described, comprising a body portion formed from a cementitious material, a face plate covering a surface of the body portion, cushioning strips engaging the edges of the face plate, and fastening means for securing the face plate to the body portion including metal frame members arranged at the edges of the block and each having a portion engaging the respective cushioning strip and another portion engaging said body portion, and a channel formed in each frame member between the back of the face plate and the body portion and spacing said face plate from said body portion.
10. A building block of the character described, comprising a body portion formed from a cementitious material, a face plate covering a surface of the body portion, cushioning strips engaging the edges of the face plate, and fastening means for securing the face plate to the body portion including metal frame members arranged at the edges of the block and each having a portion engaging the respective cushioning strip and another portion engaging said body portion, and a channel formed in each frame member between the back of the face plate and the body portion and spacing said face plate from said body portion.
11. A building block of the character described, comprising a body portion formed from a cementitious material, a face plate covering a surface of the body portion, cushioning strips engaging the edges of the face plate, fastening means for securing said face plate to said body portion including metal frame members arranged at the edges of the block and each having a portion embedded in said body portion; a channel portion arranged between the back of the face plate and the body portion and spacing said face plate from said body portion, and a second channel portion overlying an edge of the face plate and receiving the respective cushioning strip therein.
12. A building block of the character described, comprising a body portion formed from a cementitious material, a face plate covering a surface of the body portion, cushioning strips engaging the edges of the face plate, fastening means for securing said face plate to said body portion including metal frame members arranged

5 at the edges of the block and each having a portion embedded in said body portion; a channel portion arranged between the back of the face plate and the body portion and spacing said face plate from said body portion, and a second channel portion overlying an edge of the face plate and receiving the respective cushioning strip therein, said body portion extending beyond the edges of the face plate in a plane parallel with the plane of said face plate and also beyond the channel portions overlying the edges of the face plate for carrying the load of the wall when the blocks are laid up in a wall and for spacing the face plates of vertically adjacent blocks from 10 one another when said blocks are placed one upon the other whereby said face plates do not support any load of the wall.

10 13. A building block of the character described, comprising a body portion formed from a cementitious material, a face plate covering a surface of the body portion, said body portion having a ledge projecting beyond the edges of the face plate in a plane parallel with the plane of said face plate, cushioning strips engaging the edges 15 of the face plate, and fastening means for securing the face plate to the body portion including metal frame members arranged at the edges of the block and each having a portion engaging the respective cushioning strip; another portion 20 engaging said body portion and a further portion covering the outer edge of said ledge, and a channel formed in each metal frame member between the back of the face plate and the body portion and spacing said face plate from said body portion, the said ledge extending beyond 25 the edges of the face plate and also beyond those portions of the metal frame members engaging the cushioning strips upon the load supporting sides of the block to such an extent that when 30 portions of the metal frame members engaging the cushioning strips upon the load supporting sides of the block to such an extent that when

the blocks are laid up in courses in a wall, with the load bearing surfaces of the metal frame members in engagement with one another, the face plates of vertically adjacent blocks will be spaced from one another and will not support 5 any of the load of the wall.

14. A building block of the character described, comprising a body portion formed from a cementitious material, a face plate covering a surface of the body portion, said body portion being provided with a ledge projecting beyond the edges of said face plate in a plane parallel with the plane of said face plate, cushioning strips engaging the edges of the face plate, and fastening means for securing the face plate to the body portion including metal frame members arranged at the edges of the block and each having a portion overlying an edge of the face plate and engaging the respective cushioning strip; another portion 10 engaging said body portion and a further portion covering the outer edge of said ledge, and a channel formed in each metal frame member between the back of the face plate and the body portion and spacing said face plate from said body portion, the said ledge extending beyond 15 the edges of the face plate and also beyond those portions of the metal frame members engaging the cushioning strips upon the load supporting sides of the block to such an extent that when the blocks are laid up in courses in a wall, 20 with the load bearing surfaces of the metal frame members in engagement with one another, the face plates of vertically adjacent blocks will be spaced from one another and will not support 25 any of the load of the wall. 30

ERLE T. PUTNAM.
